UNITED STATES PATENT OFFICE

2,453,268

TUNING CONTROL APPARATUS

Leslie L. Royal, Chicago, Ill., assignor to Belmont
Radio Corporation, Chicago, Ill., a corporation
of Illinois

Application May 16, 1946, Serial No. 670,107

18 Claims. (Cl. 74—10)

1

The present invention relates to control apparatus for radio receivers and more particularly to manually operable automatic tuners of the mechanical type for such receivers.

Many types of modern radio receivers are provided with automatic tuning mechanisms. In general, such automatic tuners comprise a series of manually actuated push buttons which enable the listener to selectively tune in particular stations merely by pushing or actuating the push buttons. The receiver also includes manual means for tuning it to other broadcasting stations which are within its range in addition to those for which the automatic tuning arrangement, including the push buttons, is set. In one form of automatic tuner for radio receivers, a series of variably positioned cams are provided along the tuning shaft, one for each of the push buttons. Suitable cam locking means are provided for holding these cams in their predetermined positions relative to the tuning shaft so that when a push button is actuated, the associated cam is rotated with consequent rotation of the tuning shaft to a predetermined position corresponding to a particular station setting for which the push button and associated cam have been adjusted or set. In order initially to set the automatic tuning arrangement or to change the setting thereof, it is necessary to operate some means for unlocking a particular cam to the tuning shaft so that relative movement between this cam and the tuning shaft can be obtained. The present invention is particularly concerned with a new and improved arrangement for locking the cams to the tuning shaft, which locking means may be operated in a simple manner without additional equipment to afford a new setting or adjustment and is so constructed that the unlocking of any particular cam does not unlock the other cams.

Accordingly, it is an object of the present invention to provide a new and improved automatic tuning mechanism which is simple and inexpensive to manufacture, foolproof in operation, and satisfactory in every respect from the standpoint of the radio listener who operates the receiver.

A further object of the present invention is to provide a new and improved automatic tuner which can be set and reset merely by manipulation of the tuning mechanism itself without the use of extra tools and equipment.

A still further object of the present invention is to provide a new and improved manually operated automatic tuner for radio receivers

2

having a plurality of control elements on a rotary shaft with each control element adapted to be set or reset to a predetermined position independently of the other control elements and while maintaining such control elements in a fixed position on the rotary shaft.

Still another object of the present invention is to provide a new and improved cam locking means for an automatic tuner for a radio receiver or transmitter which comprises means for axially moving the cam on the tuning shaft to unlock the frictional or holding means.

Further objects and advantages of the present invention will become apparent as the following description proceeds and the features of novelty which characterize this invention will be pointed out with particularity in the claims annexed to and forming a part of this specification.

For a better understanding of the present invention, reference may be had to the accompanying drawings in which:

Fig. 1 is a perspective view of an automatic tuning mechanism embodying the present invention;

Fig. 2 is a plan view partly in section of two of the push buttons of Fig. 1 and the associated mechanism including a portion of the tuning shaft;

Fig. 3 is a view taken along line 3—3 of Fig. 2;

Fig. 4 is a view similar to Fig. 3 showing the push button operated to tune in the particular station which that push button controls;

Fig. 5 is an enlarged sectional view taken along line 5—5 of Fig. 3, and

Fig. 6 is an enlarged somewhat exaggerated view of a portion of Fig. 5 to illustrate the frictional or holding means in the released position.

Although the present invention is applicable to various forms of automatic tuners, both for radio receivers and transmitters, it has been specifically illustrated in the drawings, as applied to an automatic tuner for radio receivers.

Referring now to the drawings, there is illustrated a tuning mechanism or unit for a radio receiver which comprises a movable control element or rotary tuning shaft 10 which is suitably journalled in frame members 11 and 12 which in turn are held in spaced relationship by side pieces or frame members 13 and 14. The rotary shaft 10, which is provided with a longitudinally extending keyway 15, is coupled or otherwise connected to a suitable resonant frequency changing means for tuning the radio receiver to particular stations. In Fig. 1 of the drawings, this resonant frequency changing means is illustrated

as a variable condenser 16 having a rotor portion 17 rotatable through an angle of substantially 180 degrees with respect to a stator portion 18. It should be understood that the resonant frequency changing means might equally well comprise a variable inductance or the like. As illustrated, the variable condenser 16 is supported by a frame member 19 fastened to the frame member 12. Rotation of the tuning shaft 10 will cause the capacitance of the variable condenser 16 to vary to produce corresponding changes in the tuning of the radio set to any desired station within the range of the receiver. To accomplish this tuning, the end of shaft 10, remote from the condenser 16, is provided with a segmental gear 20 which engages with the gear 21 rotatable with a shaft 22 having a tuning knob 23 fastened thereto. Shaft 22 is preferably journalled in a frame portion 24 suitably fastened by welding or the like to frame member 11.

In accordance with the now well-known automatic mechanical tuning mechanisms for radio receivers or transmitters, the shaft 10 is also controllable by a plurality of push buttons or the like whereby particular stations to which the listener frequently desires to listen may be tuned in merely by actuating one of the push buttons which automatically causes the desired rotation to be imparted to shaft 10 without further effort than to actuate one of the push buttons.

It should be understood that each push button may be associated with a selector unit comprising members rotatably or pivotally mounted on a suitable support, or each push button may be associated with a selector unit comprising a slidable member which is moved in a generally longitudinal direction upon actuating the push button. The present invention is illustrated in connection with the latter type of selector unit, while the other type of selector unit is disclosed and claimed in a co-pending Plensler application, Serial No. 651,636 filed March 2, 1946, and assigned to the same assignee as the present application. It will be understood that a tuning unit may comprise a large number of push buttons, depending upon the number of stations to which the listener frequently desires the set to be tuned. The tuning unit of Fig. 1 has been illustrated as having a portion thereof including additional push buttons omitted, although three push buttons are specifically shown. Since all of these push buttons are identical, as are also the associated selector units, these selector units are designated by the reference numeral 25 with the associated subscript *a*, *b*, or *c*. Accordingly, in Fig. 1 of the drawings there are illustrated selector units 25a, 25b and 25c respectively. The corresponding portions of these selector units described hereinafter are designated by identical reference numerals without the subscript. As illustrated, each of the selector units 25 is provided with a manually actuatable portion or push button 26. It will be understood that a radio receiver might have as few as three or four push buttons or ten or twelve or more. The sole purpose of each individual selector unit 25 is to rotate the tuning shaft or movable control element 10 to a predetermined angular setting, which setting is different for each selector unit operated. In view of the fact that each selector unit 25 is identical in every respect, only one, namely the unit 25a, will be described hereinafter.

In order that each of the selector units such as 25a, 25b and the like, described in greater detail hereinafter, may cause a predetermined

rotation of tuning shaft 10 which is different for each selector unit, each selector unit is adapted to engage a cooperating heart-shaped cam or selecting member 27. Normally, each selecting member or control unit 25 is locked or retained against rotation relative to the tuning shaft 10 and the present invention is particularly concerned with new and improved locking or holding means, together with simple means for locking and unlocking the same, the unlocking mechanism operating only on the particular cam or control unit 27 being reset or initially set.

In brief, selector unit 25a comprises a carriage or supporting member 28 which is slidably mounted and consequently may be characterized as the main slide member to distinguish it from other slidable members to be described hereinafter. Selector unit 25a also includes, in addition to the carriage or main slide member 28, a linearly movable actuated or slidable member 29. More specifically, the carriage member 28 is of flat irregular shape best shown in Figs. 3 and 4 of the drawings, and is integrally formed with a body portion 28a and extending finger portion 28b and an extension 28c which is connected to the body portion 28a on the opposite side from finger portion 28b. The body portion 28a is provided with an integral flanged portion 28d at the lower edge thereof and a flanged portion 28e at the upper edge thereof which extends somewhat along finger 28b. The main body portion 28a is also provided near the outer edges thereof with inwardly facing L-shaped apertures 30. Between the apertures 30 is a larger aperture 31 into which extends an integral projecting portion 28f of main body portion 28a. A suitable extension or cam means 32 extends laterally from the finger 28b on the edge of finger 28b opposite flange 28e and adjacent where finger 28b joins body portion 28a. This lateral extension 32 has a cam surface 32a, the purpose of which will become apparent as the following description proceeds.

The actuated or slidable member 29 comprises a generally U-shaped member having laterally extending portions 29a and 29b at either side thereof which are adapted to fit into the L-shaped apertures 30 of carriage member 28. Preferably one of the laterally extending flanges 29a is of L-shaped configuration so that it may be inserted only into the end of aperture 30 having the right angled extension, but after it is moved along the L-shaped opening, can no longer be separated from carriage 28 unless it is moved back into this same end of the L-shaped aperture 30. The U-shaped slidable member 29 is provided with an integral projecting portion 29c so that when it is in interlocking engagement with carriage member 28, a compression spring 33 may be supported as is clearly indicated in Figs. 3 and 4 from projections 28f and 29c, respectively. When actuated member 29 is assembled with carriage member 28 so that compression spring 33 biases the lateral flanges 29b towards the end of L-shaped openings 30, remote from the right angled extension as shown in Fig. 3, the carriage member is adapted for mounting in the frame members 13 and 14. The frame member 14 is provided with openings 14a to accommodate the carriage member 28, including laterally extending aperture portions for the flanges 28e and 28f. The frame member 13, on the other hand, is provided with openings 13a sufficient to accommodate the fingers 28b. The maximum inward movement of carriage member 28 in its slidable movement relative to frame members 13 and 14, is limited

by the end of flange 28e engaging with frame member 13. A suitable tension spring member 34 connected between finger 28b and the frame member 13 normally biases the carriage 28 to the position shown in Fig. 3.

In order that the selector unit 25a may impart a predetermined rotation to shaft 10, the actuated or slideable member 29 is provided at one end thereof with a roller 35 which engages the frame member 14, as is shown in Figs. 2 and 3 of the drawings, to limit the outward movement of carriage 28. Preferably, however, the outward movement of carriage 28 is limited by cushion means on the radio cabinet not shown engaging the end of flange 28e. This roller is adapted to engage the periphery of heart-shaped cam 27 to effect rotation of the cam and consequently rotation of the tuning shaft 10 to the position indicated in Fig. 4 of the drawings where the roller 35 is positioned in the low point of the cam periphery. Normally, the compression spring 33 holds the relatively movable slideable members 28 and 29 in the relative positions shown in Figs. 3 and 4, even when sufficient force is applied to push button 26 fastened to the extension 28c of carriage 28 to rotate the cam 27 and associated tuning shaft 10 from the position shown in Fig. 4 to the position shown in Fig. 6 of the drawings.

In accordance with the present invention, each cam 27 is fastened to suitable means such as a collar member 38 rotatably mounted on the shaft 10 and furthermore mounted for limited axial movement relative thereto. Collar member 38 is provided with a pair of annular flanges 38a and 38b, as is best shown in Fig. 5 of the drawings. The cams 27 may be fastened to the collars 38 by any suitable means, such, for example, as by means of the peened-over portion 39 of the collar 38. The cam 27 and associated collar 38 are so positioned on the tuning shaft 10 that the finger 28b of the associated selector unit is slideable between the flanges 38a and 38b, respectively.

In order to hold or lock cam 27 and its associated collar 38 to shaft 10, whereby rotation of cam 27 will cause rotation of shaft 10, there is provided a friction or holding means comprising a collar 40 having suitably fastened thereto a leaf spring 41. This collar is suitably keyed to the shaft 10 as by a deformed portion 40a thereof extending into keyway 15 of the shaft. Suitable means are also provided so that the friction collar 40 and its associated leaf spring 41 are prevented from moving axially along shaft 10. Shaft 10, for example, may be provided at spaced points with suitable sawcuts 10a therein for receiving suitable stop members 42 in the form of U-shaped washers, or any other suitable means for holding the collar 40 in a fixed position relative to shaft 10 may be provided.

To hold the cam 27 in a fixed position relative to the shaft 10, it is provided with a recessed portion 27a into which the leaf spring member 41 may extend. The periphery of the recess 27a corresponds to the arc defined by the free end of the leaf spring 41 when the cam 27 is rotated relative thereto. To lock the cam 27, or to render the friction means comprising the leaf spring 41 effective, a suitable compression spring 43 axially positioned relative to tuning shaft 10 biases the collar 38 and consequently, the cam 27 toward the leaf spring 41. Spring 43 is compressed between the associated stop member 42, inserted in the sawcut or narrow portion of reduced diameter 10a in the shaft 10, and the collar 38. As illus-

trated, the collar 38 has an undercut portion 44 for accommodating the compression spring 43. As long as the spring 43 biases the collar 38 and the cam 27 into frictional engagement with the leaf spring 41, which is held in a fixed position relative to the shaft 10, the cam 27 is effectively locked to the shaft 10 so as to rotate or move as a unit therewith. Preferably the cam 27 is adjustable relative to the tuning shaft 10 through 180 degrees and suitable stop portions 27b integral with the cam 27 and extending laterally therefrom may be provided for engagement with the leaf spring 41, thereby effectively limiting the amount of rotation of the cam 27 relative to shaft 10 to 180 degrees.

In order to release the holding or friction means which effectively lock the cam 27 to the shaft 10, the lateral extension 32 having the cam portion 32a, described above, is provided for each finger 28b. When the carriage member 28 is moved to the position shown in Fig. 4 of the drawings, the slideable member 29 is prevented from moving further in a longitudinal direction toward the frame member 13 so that continued pressure applied to the carriage 28 through the push button 26 causes the compression of spring 33 until the cam surface 32a engages the flange 38a of the collar 38 to move this collar laterally or axially with respect to shaft 10, whereby the cam 27 also moves axially away from the leaf spring 41. This is clearly shown in Fig. 6 where the position of the leaf spring is exaggerated to show that it is completely free of the recessed portion 27a of cam 27. Actually, the cam 27 need not be moved axially to a sufficient extent so that the leaf spring does not even touch the cam 27. All that is necessary is that the frictional effect be reduced sufficiently so that relative movement of the cam 27 and tuning shaft 10 may take place. With the parts moved to the positions shown in Fig. 6 of the drawings, it is possible to rotate the tuning shaft 10 through manipulation of the tuning knob 23, whereby relative rotation of shaft 10 and cam 27 will occur. When the correct station is tuned in, the push button 26 is released permitting the compression spring 33 to move the main carriage 28 laterally so that the camming surface 32a frees the flange 38a from the collar 38, whereby the cam 27 moves towards the leaf spring 41 and is locked relative to the shaft 10. The tension spring 34 furthermore returns the selector unit to the position shown in Fig. 3 of the drawings.

The operation of the selector unit 25a to rotate a corresponding selecting member or cam and thereby rotate the tuning shaft 10 to a predetermined tuning position for the condenser 16 is apparent from the description included above. In setting a cam 27 to an original predetermined position or resetting it to a subsequent predetermined position, the push button 26 is actuated so that the selector unit assumes the position indicated in Fig. 4 of the drawings, whereby the cam 27 is held in a predetermined position by the roller 35. When an additional force is applied to the push button 26 in the same direction as was applied to move it from the position shown in Fig. 3 to the position shown in Fig. 4 of the drawings, the compression spring 33 is compressed and the lateral extending member 32 having the camming surface 32a engages the flange 38a of the collar 38 to move this collar and the cam 27 associated therewith axially along the shaft 10 against the force of the biasing means 43 away from the frictionally holding or locking means comprising the leaf spring 41. When this has oc-

curred, the shaft 10 is free to rotate relative to the cam 27. Accordingly, the tuning shaft 10 and the associated condenser 16 are moved to a position corresponding to the desired tuning position which will be indicated by a suitable dial on the radio receiver not shown. When this predetermined tuning position has been established, push button 26 is released and the springs 33 and 34 cause the selector unit to assume its initial position shown in Fig. 3 whereby the cam 27 is again held in locked or fixed position relative to the shaft 10. Thereafter, the push button 26 is merely used to move the selector unit from the position shown in Fig. 3 of the drawings to the position shown in Fig. 4 to tune in the predetermined station for which the cam 27 is set unless it is again desired to reset the cam 27 relative to the tuning shaft 10.

From the above description, it will be apparent that the present invention provides a simplified, sturdy, manually operable tuner for a radio receiver in which the tuning operations for initially setting or resetting the cam relative to the tuning shaft can be accomplished merely by actuating the push button and associated selector unit itself. Furthermore, a very positive arrangement for locking the cam or a plurality of cams to the tuning shaft which locking arrangement for any desired cam may be released in a simple manner. In addition, the parts of the control apparatus are simple to assemble and inexpensive to manufacture.

It will be apparent to those skilled in the art that the present invention is not limited to the particular construction shown but various changes and modifications may be made therein without departing from the spirit and scope thereof, and it is aimed in the appended claims to cover all such changes and modifications as fall within the true spirit and scope of the present invention.

I claim:

1. A control device for controllable apparatus including a rotary shaft, a control unit mounted on said shaft for relative movement therewith and capable of limited axial movement relative to said shaft, means for holding said control unit in a predetermined fixed position on said shaft, a selector unit for causing rotation of said control unit and said shaft as a unit including an actuating means, and means on said actuating means engaging said control unit for causing limited axial movement thereof to release said means for holding said control unit so that relative movement between said control unit and said shaft can be obtained.

2. A control device for controllable apparatus including a rotary shaft, a cam mounted on said shaft for relative movement therewith and capable of limited axial movement relative to said shaft, means for holding said cam in a predetermined fixed position on said shaft, a selector unit for causing rotation of said cam and said shaft as a unit including an actuating means, and means on said actuating means engaging said cam for causing limited axial movement thereof to release said means for holding said cam so that relative movement between said cam and said shaft can be obtained.

3. Tuning apparatus for a radio receiver or transmitter including a frame, a rotary tuning shaft journaled in said frame, control means on said shaft including a cam, means fixed to said shaft engaging the side of said cam, means for biasing said cam against said last mentioned

means to hold said cam in a fixed position relative to said shaft, manually operable means for engaging the edge of said cam to cause rotation of said cam and said shaft, and means associated with said manually operable means for moving said cam in an axial direction along said shaft against the force of said means for biasing said cam whereby relative movement between said cam and said shaft can be obtained.

4. Tuning apparatus for a radio receiver or transmitter including a frame, a rotary tuning shaft journaled in said frame, control means on said shaft including a cam, means fixed to said shaft including a leaf spring engaging the side of said cam, means for biasing said cam against said leaf spring to hold said cam in a fixed position relative to said shaft, manually operable means for engaging the edge of said cam to cause rotation of said cam and said shaft, and means associated with said manually operable means for moving said cam in an axial direction along said shaft against the force of said means for biasing said cam whereby relative movement between said cam and said shaft can be obtained.

5. Tuning apparatus for a radio receiver or transmitter including a frame, a rotary tuning shaft journaled in said frame, control means on said shaft including a cam, means including a leaf spring fixed to said shaft and engaging the side of said cam, means for biasing said cam against said leaf spring to hold said cam in a fixed position relative to said shaft, manually operable means for engaging the periphery of said cam to cause rotation of said cam and said shaft as a unit, and means including a camming surface associated with said manually operable means for moving said cam in an axial direction along said shaft against the force of said means for biasing said cam whereby relative movement between said cam and said shaft can be obtained.

6. A control device for a radio receiver including a rotary tuning shaft, a cam mounted on said shaft for relative movement therewith, means permitting limited axial movement of said cam relative to said shaft, a spring means fixed to said shaft, means for biasing said cam toward said spring means to hold said cam in a fixed position relative to said shaft, a selector unit for causing rotation of said cam and tuning shaft as a unit upon operation thereof, and means on said selector unit for causing axial movement of said cam away from said spring means whereby the position of said cam relative to said shaft may be varied.

7. A control device for a radio receiver including a rotary tuning shaft, a cam mounted on said shaft for relative movement therewith, means permitting limited axial movement of said cam relative to said shaft, a leaf spring means fixed to said shaft, means for biasing the side of said cam into frictional engagement with said leaf spring means to hold said cam in a fixed position relative to said shaft, a selector unit for engaging the periphery of said cam causing rotation of said cam and tuning shaft as a unit, and means on said selector unit for causing axial movement of said cam away from said leaf spring means whereby the position of said cam relative to said shaft may be varied.

8. A control device for a radio receiver including a rotary tuning shaft, a cam mounted on said shaft for relative movement therewith, means permitting limited axial movement of said cam, a leaf spring fixed to said shaft, means for biasing said cam in an axial direction toward

said leaf spring into frictional engagement therewith to hold said cam in a fixed position relative to said shaft, a selector unit including a main carriage member and an actuated member slidably related to said carriage member, means on said actuated member for engaging the periphery of said cam upon the application of force to said selector unit to cause rotation of said cam and tuning shaft as a unit, and means on said carriage member for causing axial movement of said cam away from said leaf spring upon the application of a predetermined force to said selector unit following rotation of said cam and tuning shaft as a unit whereby the position of said cam relative to said shaft may be varied.

9. In a tuning control device for a radio receiver or transmitter, a tuning shaft, a cam mounted on said shaft for both fixed or relative movement therewith, frictional means for locking said cam and said shaft in a fixed relative position, actuating means which when actuated a predetermined amount causes rotation of said cam and tuning shaft as a unit, and means adapted to engage said cam upon further actuation of said actuating means in the same direction for causing limited axial movement of said cam relative to said shaft.

10. In a tuning control device for a radio receiver or transmitter, a tuning shaft, a cam mounted on said shaft for both fixed or relative movement therewith, actuating means which when actuated a predetermined amount causes rotation of said cam and tuning shaft as a unit, and means adapted to engage said cam upon further actuation of said actuating means in the same direction for causing limited axial movement of said cam relative to said shaft.

11. A frequency control device as for a radio receiver or transmitter, including a movable control element for varying either the inductance or capacitance of a tuning circuit, a selecting member carried on said control element for both fixed or relative movement therewith, a frictional means for locking said member and said element in a fixed relative position, actuating means movable in a given direction for applying a first force to said selecting member in said given direction to move said element and said member as a unit to a position predetermined by the relative positions of said element and said member, and means carried by said actuating means and operable in response to further movement of said actuating means in said given direction for applying a second force to said selecting member substantially perpendicular to said given direction to move said selecting member relative to said frictional means.

12. A frequency control device as for a radio receiver or transmitter, including a movable control element for varying either the inductance or capacitance of a tuning circuit, a selecting member carried on said control element for both fixed or relative movement therewith, actuating means for applying a first force to said selecting member in the direction of movement of said means to move said element and said member as a unit to a position predetermined by the relative positions of said element and said member, and means carried by said actuating means and operable in response to further movement of said actuating means in the same direction as for moving said element and member as a unit for applying a second force to said selecting member substantially at right angles to the direction of said first force.

13. A frequency control device as for a radio receiver or transmitter, including a rotatable control element for varying either the inductance or capacitance of a tuning circuit, a selecting member carried on said control element for both fixed or relative movement therewith, frictional means for locking said member and said element in a fixed relative position, actuating means to rotate said element and said member as a unit to a position predetermined by the relative positions of said element and said member, and means carried by said actuating means engaging said selecting member and operable in response to further movement of said actuating means in the same direction as for rotating said element and member as a unit to cause axial movement of said selecting member relative to said rotatable control element.

14. A control device for a radio receiver including a rotary tuning shaft, a cam and associated collar member mounted on said shaft for relative movement therewith, means permitting limited axial movement of said cam, a leaf spring fixed to said shaft, means for biasing said cam in an axial direction toward said leaf spring into frictional engagement therewith to hold said cam in a fixed position relative to said shaft, means on said cam and engageable with said leaf spring for limiting the relative rotation between said cam and said leaf spring, a selector unit including a main carriage member and an actuated member slidably related to said carriage member, means on said actuated member for engaging the periphery of said cam upon the application of force to said selector unit to cause rotation of said cam and tuning shaft as a unit, and cam means on said carriage member for engaging said collar member to cause axial movement of said collar member and cam away from said leaf spring upon the continued application of a force to said selector unit following rotation of said cam and tuning shaft as a unit whereby the position of said cam relative to said shaft may be varied.

15. A control device for a radio receiver including a rotary tuning shaft, a cam and associated collar member mounted on said shaft for relative movement therewith, means permitting limited axial movement of said cam, a leaf spring fixed to said shaft, means for biasing said cam in an axial direction toward said leaf spring into frictional engagement therewith to hold said cam in a fixed position relative to said shaft, a selector unit including a main carriage member and an actuated member to predetermined relative positions, means on said actuated member for engaging the periphery of said cam upon the application of force to said selector unit having a magnitude insufficient to produce relative movement between said carriage and actuated members to cause rotation of said cam and tuning shaft as a unit, and means on said carriage member for causing axial movement of said cam away from said leaf spring upon the application of a force to said selector unit sufficient to compress said compression spring means and cause relative movement between said carriage and actuated members following rotation of said cam and tuning shaft as a unit whereby the position of said cam relative to said shaft may be varied.

16. Tuning apparatus for a radio receiver or transmitter including a rotary tuning shaft, a plurality of control units mounted on said shaft for relative movement therewith and capable of 75 independent limited axial movement relative to

said shaft, individual means for holding said control units in predetermined fixed positions on said shaft, actuating means individually associated with said control units for causing rotation of said control units, and means on each of said actuating means engaging the associated control unit for causing limited axial movement thereof in response to movement of said actuating means to release said holding means for said associated control unit, movement of each individual actuating means being entirely ineffective to release said holding means for said control units other than said control unit associated with said individual actuating means.

17. A frequency control device for a radio receiver or transmitter including a movable control element for varying either the inductance or capacitance of a tuning circuit, a plurality of selector members carried on said control element for both fixed or relative movement therewith, individual means for holding said selector members in predetermined fixed positions with respect to said control element, actuating means individually associated with said selector members for causing movement of said members and said control element as a unit, and means on each of said actuating means engaging the associated selector member for releasing said holding means for said associated selector member, movement of each individual actuating means being entirely

5

ineffective to release said holding means for said selector members other than said selector member associated with said individual actuating means.

18. In a tuning control device for a radio receiver or transmitter including a tuning shaft, a plurality of cams mounted on said shaft for both fixed or relative movement therewith, actuating means individually associated with said cams which when actuated a predetermined amount causes rotation of said cams and tuning shaft as a unit, means on each individual actuating means engaging the associated cam upon further actuation of said individual means in the same direction for causing limited axial movement of said cam relative to said shaft, movement of each individual actuating means being entirely ineffective to cause axial movement of said cams other than said cam associated with said individual actuating means.
